UNITED STATES PATENT OFFICE.

JAMES T. HOGAN, OF JERSEY CITY, NEW JERSEY, ASSIGNOR TO THE NATIONAL MACHINE COMPANY, OF NEW YORK, N. Y., A CORPORATION OF NEW YORK.

SEWING-MACHINE.

SPECIFICATION forming part of Letters Patent No. 710,150, dated September 30, 1902.

Application filed October 23, 1900. Serial No. 34,024. (No model.)

To all whom it may concern:

Be it known that I, JAMES T. HOGAN, a citizen of the United States of America, residing in Jersey City, Hudson county, and State of New Jersey, have invented a new and useful Improvement in Sewing-Machines, of which the following is a specification.

My invention relates to sewing-machines, and particularly to an attachment for suspending the vibratory movement of the needle, which may be applied to any form of over-seaming-machine in which the needle has both a reciprocating and a vibratory movement and the work-support the ordinary straightaway feed. The attachment may also be applied to machines where it is desired to sew tying-strokes, either during the sewing operation or at the completion of a cycle of movements.

For the purpose of specific illustration I have shown my invention applied to a button-sewing machine of the character described in an application filed by me December 18, 1899, Serial No. 740,642. When so applied, the needle will form a series of tying-strokes at the end of the sewing on of the button.

In order that others may understand and use my improved mechanism, I will describe the same, referring by letters to the accompanying drawings, forming part of this specification, in which—

Figure 1 is a side elevation of a sewing-machine, certain parts being broken away. Fig. 2 is an inverted plan view of the parts below the bed-plate which effect certain movements during the sewing operation. Fig. 3 is a vertical section on the plane of the line 3 3 of Fig. 1. Fig. 4 is a detailed view of the latch mechanism. Fig. 5 is a face view of the cam which vibrates the button-clamp and effects the adjustment of the latch mechanism. Fig. 6 is a detail view of a cam-lever, and Fig. 7 is a diagrammatic view showing the manner of laying strokes in sewing a button upon a machine having the present invention attached.

Similar characters indicate similar parts in the several views.

With the present form of attachment a button-sewing machine may be operated to sew

four-holed buttons or two-holed buttons, as may be desired. I will first describe the construction and the method of operation for sewing four-holed buttons and then the changes that may be made to sew two-holed buttons. 55 Whatever the character of the button to be sewed, whether four-holed or two-holed, the purpose is to tie the thread at the end of the sewing operation to prevent raveling.

A designates the bed-plate, and A' the head, 60 of a machine of the usual construction; A², the main shaft, which may be driven in any suitable manner; B⁴, the needle-bar carrying the needle b⁴, the said bar being mounted in the frame and reciprocated by the usual connection from the shaft A². The needle-bar B⁴ is also given a vibratory movement by the pitman B², attached to the main rock-lever B'.

E designates any suitable form of button holder or clamp.

Instead of connecting the lever B' directly to the cam B, as is usual, I provide the mechanism which I will now describe.

C designates a shaft mounted in suitable 75 bearings in the head of the machine. This shaft has rigidly secured thereto a supplementary rock-lever D, which carries upon its under face a stud and follower d², which follower travels in the groove of a cam B. This cam is of the usual form of construction, forming part of a bevel-gear A³, which meshes with a corresponding gear A⁴ on the main driving-shaft A². By means of the cam B a rocking movement is given to the shaft C 80 and the attached lever D.

The lever D serves as a support and a guide for a latch-carrier L. This latch-carrier is slotted near its lower end, as shown at l, to receive the shaft C, the slot permitting lengthwise movement of the latch-carrier. The lever D is provided near its upper end with guide projections d and d', the former projecting beyond the edge of the latch-carrier L, so as to form a stop for the forward movement of the lever B'. The latch-carrier has secured at its upper end a plate L', having a projecting finger e', this plate and finger forming a latch to lock the lever B', which lever is mounted loosely on the shaft C, so 95 100

that it shall partake of the rocking movement of the lever D and latch-carrier L by the cam B, a notch b' being provided in the upper edge of the lever B' to receive the finger e' . The pitman B² is secured to the stud b^2 , clamped to the lever B'. The rocking movement of the lever B' will impart a vibratory movement to the needle. The amplitude of this vibratory movement may be regulated at will by adjusting the position of the stud b^2 in the slot b^8 of the lever B'. The spring b^5 serves to draw back the lever B' against the stop-pin b^6 when the said lever is unlocked and to hold it in proper locking position.

In my button-sewing application, Serial No. 740,642, the needle-bar and button-holder are simultaneously vibrated in directions at right angles to each other. The vibratory movement of the button-clamp is effected by means of a suitably-constructed cam. This cam I have so modified in the present construction as to effect the suspension of the vibratory movement of both the button-holder and the needle at the end of the ordinary sewing operation, so as to give any suitable number of tying-strokes. This cam is mounted on a stud on the under side of the bed-plate of the machine and is given a rotary movement by means of the lever H², actuated from the main driving-shaft, the pawl-carrying lever H³, and ratchet-wheel H'. The button-holder is secured to a plate actuated by a lever G, to which lever is secured a follower g', engaging the cam H. A face view of the cam H is shown in Fig. 5 divided by radii, so as to make clear the exact movements of the button-holder. At the beginning of the sewing operation the needle is at the limit of its upper throw and the cam-follower is intermediate the space 18 and 1. The cam travels in the direction of the arrow and imparts a vibratory movement to the button-holder, except for the dwells in the spaces 9, 16, 17, and 18. By the simultaneous vibration of the needle and button-holder a series of eight stitches will be sewed between the holes 1 2, Fig. 7. While the follower is in the space 9 of the cam H the vibratory movement of the button-holder is suspended, but that of the needle continues. This gives the cross-stitch between the holes 2 3. The vibratory movement of the button-holder is then resumed and six stitches sewed between the holes 3 4. At this point it is necessary to suspend the vibratory movement of both needle and button-holder.

The vibratory movement of the button-holder is suspended by the cam-follower g' passing into the sections marked 16, 17, and 18 of the cam H. The means by which the vibratory movement of the needle is suspended are as follows: Attached to the edge of the cam H is a plate F, having one end in the form of a cam f. This plate F corresponds in length to the length of the dwell 16 18 of the cam-groove, so that the suspension of the

vibratory movement of the button-holder and needle shall be of the same duration. When the cam-follower passes into the dwell 16 18, 70 the cam-point of the plate F contacts with the projection i on a lever I. The projection i may be an integral part of the lever I, or, as shown, it may be separate, forming part of a plate i', which latter will be secured to the 75 lever I with screws. This lever I is fulcrumed on a pin in a bracket I², secured to the under side of the bed-plate, and its forward end rests on a collar I³, secured to the end of a vertical shaft O. A lever M, fulcrumed on 80 a stud in a suitable hanger, is secured to the upper end of the vertical shaft O, the forward end of the lever M resting in a curved slot l² of the latch-carrier L. It is evident from this construction that when the vertical shaft O 85 is depressed by the cam-plate F the forward end of the lever M will be pressed against the upper edge of the slot l². This movement of the lever M will raise the latch-carrier L to release the finger e' from the notch b' of the 90 lever B'. When the lever B' is thus released, it is clear that while the vibratory movement of the latch-carrier L continues no vibratory movement will be given the said lever, and the vibratory movement of the needle will 95 then be suspended. The spring b⁵ draws the lever B' when it has been released to the position shown in Fig. 4. The length of the dwell 16 18 of the plate F is such that three 100 tying-strokes will be sewed. When the cam-follower g' reaches the end of portion 18 of the cam H, a stop-motion, which will be attached to the machine, will come into operation. This will bring the machine to a stop as the needle reaches the limit of its upper throw and 105 in a position to begin the sewing of a new button. Any suitable stop-motion may be employed—for example, that shown in a patent granted to me March 6, 1900, No. 644,801. The cam B is so timed that when the needle is at its 110 upper throw the latch-carrier L will be thrown to its extreme position at the right, and as the plate F passes out of contact with the cam-lever I the spring O', which is seated between collars on the shaft O, will lower the outer 115 end of the lever M so as to bring the finger e' into the notch b', thus locking the lever B' in such position that it will be vibrated by the cam B.

If it is desired to sew a two-holed button, 120 I may do so by suspending either the vibratory movement of the needle or of the button-holder. To suspend the vibratory movement of the needle, the screw-cap b⁷, which retains the end of the pitman B² on the stud 125 b², is removed and the pitman connected to the stud b⁸, which stud is a part of the shaft C or is secured thereto and coincident with its axis. When the pitman B² is thus connected, it is clear that no vibratory movement will be imparted to it. The vibratory movement of the button-holder continues so 130 as to sew eight stitches between the two holes, then one tying-stitch, while the follower

is in the space marked 9 of the cam H, then six more stitches, and finally three tying stitches.

To sew two-holed buttons by the vibratory movement of the needle only, I remove the cam-follower g', when no vibratory movement can be imparted to the button-holder. The cam, however, continues to rotate, and at the proper time the cam-plate F will actuate the lever I to release the lever B' from the latch L'. The cam B imparts the vibratory movement to the pitman B², and the lever B' is released to give three tying-strokes at the end of the sewing operation corresponding to the dwell 16 18 of the cam H. When the cam-plate F passes out of engagement with the lever I, the lever B' will be locked to the latch-carrier L in the manner before described.

Any desired number of stitches may be sewed, and I have merely for the purpose of convenience in description shown the cam as constructed in Fig. 5. Whatever the number of divisions of the cam H may be the number of teeth on the ratchet-wheel H' will correspond thereto. This correspondence insures accurate timing of the parts, for whatever may be the position of the follower in the cam H the movements of the button-holder and of the lever M will follow each other in the order necessary to secure the results described.

While I have described my invention in connection with a button-sewing machine, it is to be distinctly understood that I do not limit myself thereto, as the above-described attachment for suspending the vibratory movement of the needle-bar may be used on overseaming-machines. Any suitable cam may be employed in such case to trip the lever M, or it may be tripped by hand through a suitable connection, as P, to depress the shaft O. When so used, a series of overseaming-strokes may be sewed and then the vibratory movement of the needle suspended while straight stitches are being sewed, then the overseaming resumed at will or according to the particular pattern-cam employed.

What I desire to claim and secure by Letters Patent is—

1. In a sewing-machine the combination with stitch-forming mechanism comprising a vertical reciprocating needle, of a work-support, means to feed said support, a rock-lever and means to actuate the same, a pitman connecting said lever and the needle-bar frame, and means to simultaneously suspend the movements of said lever and the feed of the

work-support at the end of the sewing of a cycle of stitches while the vertical reciprocating movement of the needle continues, to permit the sewing of tying-strokes, substantially as described.

2. In a sewing-machine the combination with stitch-forming mechanism, of a work-support, means for simultaneously vibrating the needle and work-support and means to automatically and periodically suspend the vibratory movement of both of said devices at the same time to permit tying-strokes to be sewed, substantially as described.

3. In a sewing-machine the combination with stitch-forming mechanism, of a work-support, a cam for imparting to the work-support a vibratory movement, means for imparting to the needle a vibratory movement in a direction at right angles to the plane of movement of the work-support, a lever actuated by said cam to suspend the vibratory movement of the needle, said cam being so constructed as to cause the suspension at the same time of the vibratory movement of the work-support, substantially as described.

4. In a sewing-machine the combination with stitch-forming mechanism, of a work-support, a rock-shaft, a lever rigidly secured to said shaft and engaging a cam, a main rock-lever loosely mounted on said shaft, a pitman connecting said last-named lever to the needle-bar, a latch connection between said levers, a cam and suitable connections to impart to the work-support a vibratory movement, levers between the said last-named cam and said latch mechanism, said cam being so constructed as to simultaneously suspend the vibratory movement of the work-support and to release said latch to permit the sewing of tying-strokes, substantially as described.

5. In a sewing-machine the combination with stitch-forming mechanism comprising a vertically-reciprocating needle, of a work-support, means to vibrate said work-support in a given path relatively to the needle and means to automatically suspend said vibratory movement while the vertically-reciprocating movement of the needle continues, to permit the sewing of tying-strokes, substantially as described.

In testimony whereof I have signed my name to this specification in the presence of two subscribing witnesses.

JAMES T. HOGAN.
